UNITED STATES PATENT OFFICE.

EDWIN W. ROGERS AND CHARLES C. CHAPEL, OF MARSHFIELD, WISCONSIN.

TYPGRAPHICAL MACHINE.

1,388,764.

Specification of Letters Patent. Patented Aug. 23, 1921.

Application filed March 8, 1921. Serial No. 450,522.

To all whom it may concern:

Be it known that we, EDWIN W. ROGERS and CHARLES C. CHAPEL, both citizens of the United States, and residents of Marshfield, 5 in the county of Wood and State of Wisconsin, have invented certain new and useful Improvements in Typographical Machines; and we do hereby declare that the following is a full, clear, and exact description thereof.

10 Our invention refers to linotype or type-setting machines, and it has for its primary object to provide means for materially increasing the speed of such machines, and efficiency of the operator, by dispensing 15 with one complete hand operation of the machine, which ordinarily entails the removal of the hands from the keyboard, for the purpose of raising or lowering the assembling elevator efficiently, whereby lost 20 motion is overcome, due to movement back and forth of the operator's hands from the keyboard to the usual standard hand controlled lever, which raises and lowers the assembling elevator. Hence, our improve- 25 ment will leave the mind and the hands of the operator free to perform the ordinary keyboard functions, and judgment or pre- caution can be dispensed with in raising and lowering the elevator, due to the fact that 30 the problem, as we have solved it, is an arrangement of a foot controlled means whereby the elevator is raised or lowered and cushioned at the end of movements.

Another object of our invention is to connect the assembling elevator with a foot treadle operating means, having some form of interposed cushion whereby the starting movement and the finishing movement of the assembling elevator is gradual or retarded, 40 to thus eliminate shock in the start and finish of the elevator action.

Another object of our invention is to provide a foot controlled lever connected to the elevator, having a coil spring shock absorber 45 means interposed therein, whereby when the elevator is full down, the coil spring is compressed, and when full up, the same is again compressed to thus absorb the shock. In other words, when in a machine equipped 50 with our invention, the elevator is in its upward movement, it starts with a short lever- age and thereafter increases and develops speed by action on a long lever until the elevator reaches approximately the full height 55 of its travel, at which time it engages the standard stop and shock of this sudden stop

is absorbed by a yield of the spring mechanism.

With the above and other objects in view, the invention consists in certain peculiarities 60 of construction and combination of parts, as are hereinafter set forth with reference to the accompanying drawings and subsequently claimed.

In the drawings:

Figure 1 represents a fragmentary face view of a standard linotype matrix assembling device or elevator, having attached thereto a foot actuating mechanism embodying the features of our invention, the elevator being shown in an intermediate position with relation to its up and down movement, and as having stops for limiting such movement, the said stops being diagrammatically expressed.

Fig. 2 is an enlarged detailed plan view of a foot controlled mechanism embodying the features of our invention, the same having parts broken away and in section to show certain structural features, and

Fig. 3 is an end view of the foot controlled lever mechanism, the same being shown in its raised position in full lines, and in its extreme depressed position in dotted lines.

Referring by characters to the drawings, A represents a matrix assembling elevator, which is adapted to reciprocate in a track or frame B. The reciprocative movement of the elevator is controlled by stops, and in Fig. 1 of the drawings are illustrated diagrammatically, as at a—a, it being understood that the elevator is shown in its intermediate position for clearness of illustration.

One leg C of the machine, in this particular instance, is used for securing thereto a bearing bracket 1 by suitable set screws, it being understood, however, that when our device is used as a "built-in structure," a suitable bearing bracket may be cast from the base of the machine. The bearing bracket 1, has journalized therein a rock shaft 2, one end of which has secured thereto a foot treadle 3, whereby the shaft may be rocked in either direction. The other end of the shaft 2 is formed with a right angle extension pad 2', to which is secured an apertured ear 4 that extends at a right angle to the foot. The ear has fitted therein a headed bolt 5, which bolt also passes through an apertured foot 4' of a rock arm 6. The rock arm is arranged to nest snugly against one

wall of the pad 2', whereby it is guided and its foot terminal 4' is held, under normal conditions, in snug contact with the ear 4 of the pad by a coil spring 7, which surrounds the bolt 5 and is interposed between the foot 4' and a washer 8' that is adjustably confined by a nut 8 in threaded union with the upper end of the bolt 5.

- The forward end of the rock arm 6 is pivotally connected to a link in the form of a bell crank lever having a short arm 9 and a long arm 9'. The short arm of the bell crank is arranged to travel in an arc of a circle, parallel with the rock arm 6, the said short arm 9 being limited in its movement in either direction by stop lugs 10 10', which lugs constitute part of a bracket that is adjustably secured by a bolt 11 to the rock arm 6. Hence, it will be seen that by adjusting the bracket and its associated lug toward or away from the fulcrum point of the bell crank lever, its swing upon said fulcrum point may be predeterminedly controlled.

- The upper end of the long arm 9' of the bell crank lever has fitted thereto an adjustable strap portion 12, which strap portion is held against movement after a predetermined adjustment by a clip 13 that surrounds the companion parts of the bell crank lever, the same being locked by a set screw 13'. Hence, the long arm of the bell crank lever can be lengthened or shortened for adjustment to the various conditions of machines, to which the devices apply.
- In this exemplification of my invention, as shown in Fig. 1, a link C' has one end connected to the assembling elevator, and the other end connected to the upper end of the strap portion 12 of the bell crank lever by a set screw 14. This link C' or its equivalent, in a standard machine, is employed for connection to a hand controlled lever not shown, whereby the elevator is raised or lowered.

- Attention is directed to the fact that the spring controlled hinge joint between the rock shaft 2 and rock arm 6 is capable of adjustment, whereby yield between these hinged parts is predeterminedly regulated.

- From the foregoing description, it will be seen that when the foot pedal is actuated to raise the assembling elevator, the parts are in the position indicated in dotted lines of Fig. 3. The initial positive lifting action from the foot pedal will thus be momentarily retarded, until such time as the spring controlled hinge joint between the arm and rock shaft closes, it being understood that it is normally broken when the previous down stroke of the elevator was completed, due to the fact that the elevator was positively stopped in said down movement.

- Hence, the first impulse of the operator in lifting will be absorbed so as to prevent a sudden shock upon the elevator, and thereafter the elevator will be lifted gradually,

as the rock arm rises until such time as the elevator comes to a point near the finish of its lift, at which time the short arm 9 of the bell crank will engage the stop 10 of the rock arm, and thus the rock arm and bell crank being locked together, the spring will now come into play as a cushion, and the hinge joint will be broken slightly, as indicated in full lines in Fig. 3. In other words, after the elevator starts to rise, it will move at a slow speed and thereafter it will travel at a higher speed to a point just before it finishes its upward stroke, at which time the speed or lift will be slowed up, prior to the elevator coming against a positive stop or bumper a. This cushioning of the stroke is accomplished by the shock absorbing spring and the jointed rock arm connected between the rock shaft.

In practice, by actual demonstration, it has been found that by the use of this foot control mechanism, under normal conditions, the speed of the operator can be increased 30%, due to the fact that the hands of the operator are entirely free at all times to manipulate the keys, and his mind can be at all times concentrated upon the keyboard and work. Under the old conditions, where a hand lever was used, operators found it necessary to leave the keyboard and use one hand for lifting or lowering the elevator, and the other hand was utilized to grasp the elevator and retard it in its movement in either direction. All of this hand work has been thus dispensed with. Obviously, while we have shown and described one specific means of carrying out our invention, we may, without departing from the spirit of the said invention vary such details within the scope of the claims as they may be hereinafter interpreted by those skilled in the art.

We claim:

1. In a linotype machine having a vertically reciprocative matrix assembling elevator; the combination of a raising and lowering mechanism therefor, the same including a foot controlled rock shaft, a rock arm yieldably secured thereto, a link pivoted to the arm and connected to the elevator, the yielding connection between the rock arm and shaft serving to cushion the starting and stopping movement imparted to said elevator by foot power.

2. In a linotype machine having a vertically reciprocative matrix assembling elevator; the combination of a raising and lowering mechanism therefor, the same including a foot controlled rock shaft, an arm hingedly connected thereto, a spring mechanism for resisting the hinge action of said arm in both directions, and a link connecting the arm and assembling mechanism.

3. In a linotype machine having a vertically reciprocative matrix assembling ele-

vator; the combination of a raising and lowering mechanism therefor, the same including a foot controlled rock shaft, an arm hingedly connected thereto, a spring mechanism for resisting the hinge action of said arm in both directions, means for tensioning the spring mechanism and a link connecting the arm and assembling elevator.

4. In a linotype machine having a vertically reciprocative matrix assembling elevator; the combination of a raising and lowering mechanism therefor, the same including a foot controlled rock shaft, an arm hingedly connected thereto, a spring mechanism for resisting the hinge action of said arm in both directions, stops carried by the rock arm, a bell-crank lever in pivotal union with the end of said rock arm having a short arm adapted to engage the stops, the other arm of the bell-crank lever being in link connection with the assembling elevator.

5. In a linotype machine having a vertically reciprocative matrix assembling elevator; the combination of a raising and lowering mechanism therefor, comprising a journal bracket adapted to be secured to the base of the linotype machine, a rock shaft mounted therein having a foot treadle at one end, an arm yieldably secured to the rock shaft, and a link mechanism connecting the outer end of the arm and the matrix assembling elevator, the yielding connection between the rock arm and rock shaft serving to cushion the start and stop movement imparted to the elevator by the application of foot power to the treadle in either direction.

In testimony that we claim the foregoing we have hereunto set our hands at Marshfield, in the county of Wood and State of Wisconsin.

EDWIN W. ROGERS.
CHARLES C. CHAPEL.
